GASOLINE DISPENSING PUMP

Harry G. Smith, Pasadena, Calif., assignor to A. O. Smith Corporation, Milwaukee, Wis., a corporation of Wisconsin

Application September 15, 1958, Serial No. 52,640

Term of patent 14 years

(Cl. D52—2)

Fig. 1.

Fig. 2.

Figure 1 is a perspective view showing the front and one side of the gasoline dispensing pump embodying my new design; and

Fig. 2 is an elevational view of the opposite side of the pump.

The rear of the pump is the same in appearance as the front.

I claim:

The ornamental design for a gasoline dispensing pump, substantially as shown and described.
